CLAIM

The ornamental design for a strapping tool, as shown and described.

DESCRIPTION

FIG. 1 is a front top right-side perspective view of a strapping tool of one embodiment of my new design.

FIG. 2 is a front elevational view of the strapping tool of FIG. 1.

FIG. 3 is a rear elevational view of the strapping tool of FIG. 1.

FIG. 4 is a right-side elevational view of the strapping tool of FIG. 1.

FIG. 5 is a left-side elevational view of the strapping tool of FIG. 1.

FIG. 6 is a top plan view of the strapping tool of FIG. 1; and, FIG. 7 is a bottom plan view of the strapping tool of FIG. 1. The broken lines showing parts of the strapping tool form no part of the claimed design.
